[57] CLAIM

The ornamental design for a tool for disengaging an electrical connector terminal, as shown.

DESCRIPTION

FIG. 1 is a perspective view of a tool for disengaging an electrical connector terminal showing my new design in actual use;

FIG. 2 is a front elevation view thereof, the rear elevation view being a mirror image;

FIG. 3 is a top plan view thereof;

FIG. 4 is a bottom plan view thereof;

FIG. 5 is a left elevation view thereof; and,

FIG. 6 is a right elevation view thereof.

FIG 1

FIG 2

FIG 3

FIG 4

FIG 5

FIG 6
